CLAIM

The ornamental design for an combined alarm with light, as shown and described.

DESCRIPTION

FIG. 1 is a perspective view of an combined alarm with light showing the claimed design;

FIG. 2 is a perspective view of an combined alarm with light thereof;

FIG. 3 is a front view thereof;

FIG. 4 is a back view thereof;

FIG. 5 is a right side view thereof;

FIG. 6 is a left side view thereof;

FIG. 7 is a top view thereof; and,

FIG. 8 is a bottom view thereof.

The broken lines in the drawings depict portions of the combined alarm with light that form no part of the claimed design.

1 Claim, 3 Drawing Sheets
